FRANCIS BETTS SMITH, OF SAN FRANCISCO, CALIFORNIA.

METHOD OF POSITIONING AND ALIGNING STRUCTURES IN AQUEOUS BODIES.

Application filed March 31, 1926. Serial No. 98,854.

This invention relates primarily to a structure, its foundation, and the method of submerging the same and aligning it, if necessary, with previously submerged and aligned sections in aqueous bodies.

The invention consists primarily in providing a form of body and foundation block relatively to which the same is supported when submerged and which body and foundation block are associated in such manner as to render their submergence a relatively easy matter. The invention further consists in utilizing the foundation blocks to overcome the buoyancy of the structure while suspended therefrom, the structure being of itself buoyant when the foundation blocks rest on a base, there being provided adjustable connections between the foundation blocks and structures, enabling the positioning of the structure to line and level while floating relatively to the foundation blocks resting on the bed.

The invention consists further in the simple method employed for quickly and readily submerging and bending the bodies and blocks accurately to line and level and at relatively little cost in the comparison with the complicated methods now in use.

In the drawings, disclosing one embodiment of my invention—

Fig. 1 is a view in perspective of a tubular structure of a size to be employed as a subway, there being illustrated, adjustably suspended therefrom at its ends, suitable foundation blocks and removable and closing means to enable the tubular structure to be maintained buoyant.

Fig. 2 is a view in perspective of two sections of the structure after the same have been submerged and aligned to line and level on a prepared bed and prior to the rendering of the last section non-buoyant and the bedding thereof.

Fig. 3 is a view in side elevation, particularly in section, of the end joint connection between two sections, illustrating the adjustable turn buckle connections.

Fig. 4 is an end view of one of the tubular structures, disclosing the foundation blocks suspending therefrom and the manner of adjustably uniting the same to the end flanges of the structure.

In the drawings, wherein is disclosed the embodiment of the invention as applied to a

tubular structure—the numeral 1 indicates a body preferably of elongated tubular form, in the present instance the same being of sufficient diameter to allow the same to be used as a subway or viaduct under aqueous bodies. The structure 1 may be of any suitable material, concrete, steel or the like, and is of the necessary length for the results desired. At its opposite end the structure 1 is provided inwardly of its internal ends with radial end wall flanges 2, the bases of which are increased in thickness at 3 and extend transversely beneath the structure 1. The positioning of the end flanges 2 inwardly of the terminal ends of the structure 1 affords an end extension 4 projecting beyond the outer face of the respective flanges 2.

Suspended beneath each end flange 2 is a foundation structure, illustrated in the present invention, as consisting of duplicate blocks 5, arranged in end to end relation, parallel with the underside of the thickened portion 3 of the end flange 2. Each of these foundation blocks 5 is suspended from the underside of the flange 2 by adjustable turn buckle connections 6, conventionally illustrated, the opposite ends of the turn buckle connections being secured respectively to the eye members 7 and 8 carried respectively by the end flanges 2 and foundation blocks 5. Adjustable lateral guys 9 are provided for adjusting the ends of the structure longitudinally of the foundation blocks. The end flanges 2 are also provided with eyes 10 adapted to oppose each other on the setting of aligned sections, as in Figs. 1 to 3 inclusive, and to be united by adjustable turn buckle connections 11.

After successive structures have been submerged and aligned to line and level by a method hereinafter described, suitable forms 12 unite the opposing vertical edges of adjacent flanges 2, as in Fig. 2 of the drawings, and enable concrete or other sealing medium 13 to be poured to enclose and seal the joint connection between adjacent structures.

In submerging and positioning the structures to line and level within aqueous bodies, the following method is preferred:

A foundation or sub-grade is preferably prepared to receive the structure sections and this may be prepared within a reasonable degree of accuracy, either by straight edging broken stone by means of a girder or

by driving piles and cutting them off, the cut ends to afford a support for the structure foundation blocks.

The ends of the tubular structure 1 are 5 then closed by suitable removable end walls 14 to provide air chambers within the structures, maintaining the same buoyant.

To the bottom edges of the end flanges 2 are then suspended the foundation blocks 5 10 which are of a combined weight sufficient with the aid of a ballast within the structure 1 to overcome the buoyancy of the structure and to cause a sinking thereof of within the aqueous body within which 15 the structure is to be submerged by suitable derricks, tackle and rigging. The buoyant structure is towed to overlie its position of submergence and when approximately overlying such position, the same is lowered or 20 allowed to sink, instruments not shown being employed to maintain the same generally on line and level. As the foundation blocks 5 rest on the straight edged rock surfaces 15, overlying the back fill 16 of hard 25 material, the release of the weight thereof renders the structure buoyant and the same floats, straining on the adjustable connections 6 and 9.

With the end of the structure positioned 30 to coact with the end of the previously submerged or positioned structure with which it is to align, the adjustable connections 6 and 9 are tightened or loosened, as the case may be, to align the buoyant section to line 35 and level.

When this is accomplished the wedges or other supports 17 are positioned between the lower edge of the flange 2 and the upper surface of the foundation blocks 5 to hold 40 the two in the desired position. The adjustable connections 11 between corresponding ends of adjacent structures are then tightened and the submerged structure is in a position to be bedded in suitable bedding 45 material, such as broken stone and the like, to be positioned around the same.

As previously described, the end joints of the adjacent sections are sealed and made 50 water proof and, if necessary, material is tamped in or filled in between the lower edge of the end flanges and the upper surface of the foundation blocks. After these operations are completed, the structure is rendered 55 non-buoyant by releasing the air confined therein, in any suitable manner.

While this invention has been illustrated and described in this application in connection with a tubular body with its ends closed to provide a buoyant body, it is to be understood 60 that the same is adapted for use in the positioning or floating box caissons in their use in the construction of breakwaters and sea walls.

It is to be understood that while I describe 65 the structure employed in the present

embodiment as tubular and provided with closed ends to afford buoyancy, it is to be understood that solid structures may be employed and ballast chambers used in connection therewith to provide buoyancy.

70

I claim:

1. The method of submerging and aligning structures in aqueous bodies, which consists in lowering on to a bed a structure rendered buoyant with foundation members adjustably suspended therefrom which overcome the buoyancy thereof while suspended with the foundation members resting on the bed and maintaining the structure submerged, adjusting the suspension connections to properly position the structure to line and level, and bedding the positioned structure.

75

2. The method of submerging and aligning structures in aqueous bodies, which consists in lowering a buoyant structure with foundation members adjustably suspended therefrom, which overcome its buoyancy on to a prepared bed with the foundation members resting on the bed and maintaining the structure submerged, adjusting the suspension connections to properly position the structure relatively to the bed and foundation members, bedding the positioned structure, and thereafter rendering the same 90 non-buoyant.

95

3. The method of submerging and aligning structures in aqueous bodies, which consists in preparing a bed to support the structure, rendering the structure buoyant, adjustably securing to the structure foundation members of sufficient weight to overcome the buoyancy of the structure, lowering the structure with its foundation members on to the prepared bed, with the foundation members resting thereon with the structure remaining buoyant, adjusting the connections between the structure and foundation members to position the structure to line and level, bedding the structure, and thereafter rendering the structure nonbuoyant.

100

4. The method of submerging and aligning structures in aqueous bodies which consists in lowering on to a bed foundation blocks connected through adjustable connections with a buoyant structure, the foundation blocks being of sufficient weight to overcome the buoyancy of the structure, adjusting the structure and foundation connections to position the structure to line and level, and bedding the structure.

105

5. The method of submerging and aligning structures in aqueous bodies which consists in lowering on to a bed foundation blocks connected through adjustable connections with a buoyant structure, the foundation blocks being of sufficient weight to overcome the buoyancy of the structure, adjusting the structure and foundation connections to position the structure to line and level,

115

120

125

130

rendering the structure non-buoyant, and bedding the structure.

6. A structure for submerging in aqueous bodies, comprising a body having foundation blocks suspended therefrom, and adjustable connections between the respective foundation blocks and the body.

7. A structure for submerging in aqueous bodies, comprising a body having foundation blocks suspended therefrom and disposed transversely beneath the same near its opposite ends, adjustable connections between the respective foundation blocks and the body whereby relative adjustment be-

tween the foundation blocks and the body 15 may be obtained.

8. A structure for submerging in aqueous bodies, comprising a tubular body having radial flanges extended therefrom inwardly of its opposite ends, a foundation block suspended from the underside of each end flange, and adjustable connections uniting the foundation blocks to the respective end flanges.

In testimony whereof I have signed my 25 name to this specification.

FRANCIS BETTS SMITH.
